UNITED STATES PATENT OFFICE.

HARVEY A. EICHELBERGER AND JOHN D. EICHELBERGER, OF ST. LOUIS, MISSOURI.

LAUNDRY DEVICE.

1,286,565.

Specification of Letters Patent.

Patented Dec. 3, 1918.

Application filed March 22, 1918. Serial No. 223,957.

To all whom it may concern:

Be it known that we, HARVEY A. EICHELBERGER and JOHN D. EICHELBERGER, citizens of the United States, residing in the city of 5 St. Louis and State of Missouri, have invented new and useful Improvements in Laundry Devices, of which the following is a specification.

This invention relates to laundry devices 10 and more particularly to an apparatus or machine for the washing, rinsing and wringing of wearing apparel and other articles. It has for its principal objects to minimize manual labor and to obviate the necessity 15 for placing the hands in the water in carrying out the processes above mentioned, particularly in rinsing and wringing the water out of the washed articles.

The invention consists in an apparatus 20 and in the parts and combinations and arrangements of parts, as hereinafter described and set forth in the appended claims.

In the accompanying drawings illustrating 25 a practical embodiment of the invention,—

Figure 1 is a view, partly in side elevation and partly in section, showing the apparatus as arranged for washing;

Fig. 2 is a top plan view, parts being 30 broken away to show more clearly the construction and arrangement of the removable cover for the receptacle;

Fig. 3 is a plan view of the presser or 35 squeezer disk detached;

Fig. 4 is a fragmentary detail view of a portion of the actuating mechanism for the 40 agitator;

Fig. 5 is a vertical section showing the 45 squeezer mechanism placed in operative position;

Fig. 6 is a fragmentary section on the line 6—6 of Fig. 5;

Fig. 7 is a section, similar to that shown 50 in Fig. 5, illustrating a modification of the squeezer mechanism, and

Fig. 8 is a fragmentary detail view showing the manner in which the agitator is mounted.

Referring now to the drawings, the 55 numeral 1 indicates the receptacle or tub. Preferably, the outside of the tub is tapered to support the hoops 2, but the inside is cylindrical and may be corrugated vertically according to the common practice, or not, as desired. So, too, the tub may or may not have the usual feet or legs 3, as desired.

At the top of the tub is a removable clo-

sure or lid comprising two half sections 4, 5, with a central opening 6 for the accommodation of the spindle of the agitator to 60 be later described. This lid, when in place, is a little below the upper edge of the tub, and the respective sections 4, 5, are supported by clips 7 having upwardly offset, projecting outer end portions which rest on the 65 tub. The section 5 has a pair of cleats 8 fastened on its top face, as at 9, and extending over the section 4, but without attachment thereto. The top faces of these cleats 8 come substantially flush with the edge of 70 the tub and they have clips 10 thereon and projecting so as to rest on the tub.

On a supporting frame 11 which is fastened on one side of the tub, are two upstanding bearing brackets 12 for a driving 75 shaft 13. Hingedly mounted at one end on the shaft 13, as by bearing brackets 14, is a bridge-plate or member 15 having a leg 16 at its opposite end to rest on the edge of the tub (see Fig. 1), so as to support the bridge- 80 plate in horizontal position, and in which position it is fastened by a suitable catch 17. This bridge-plate carries the actuating mechanism for the agitator now to be described.

On the bridge-plate 15 is a housing 18 in which is mounted a pinion 19, said pinion having fixed thereto the spindle 20 of the agitator. Slidably mounted on the housing 18 is a rack-bar 21 which has its teeth in engagement with said pinion 19. This rack-bar is connected by a link or pitman 22 to a crank arm 23 on the end of the driving shaft 13; and said driving shaft 13 has on its opposite end a hand wheel or a suitable pulley 24 or other actuating means, whereby a reciprocatory motion may be imparted to the rack-bar 21 and it in turn effects an oscillation of the pinion 19 and the attached spindle 20.

Mounted loosely on the spindle 20 is an agitator disk 25 having pegs or fingers 26 for engaging the articles to be washed in the tub. To permit the disk 25 in action to slide longitudinally on the spindle 20 and 105 at the same time hold it from rotating independently thereof, the spindle is provided near its end and on opposite sides with ribs or fins 27 and the central opening 28 of the disk is correspondingly notched, as at 29, 110 to loosely fit the portion of the spindle so formed. To retain the agitator disk on the spindle the latter has a suitable knob or collar 30 at its end.

To adapt the agitator mechanism for use with an adjacent or adjoining, or a twin tub, the spindle may be extended on the opposite side of the pinion 19, as at 20^a and 5 made as an exact duplicate as just above described, and have thereon a second agitator disk 25^a. In this way, a second tub may be placed alongside of the tub 1 and the bridge-plate 15 swung over thereon so as to rest 10 with its leg 16^a (opposed to the leg 16) on the edge of said second tub, where it may be fastened by the catch 17^a. Obviously, as the center of the driving shaft 13 is to one side of the bridge-plate 15 (see Fig. 1) the portion 20^a of the agitator spindle and the leg 16^a are made correspondingly longer than the parts 20 and 16; otherwise, the second tub should be correspondingly elevated.

The wringing or squeezer mechanism will 20 now be described. This comprises a follower or squeezer disk 31 movable vertically in the tub 1, and, preferably, having its upper face corrugated, as at 32, and being perforated, as at 33, throughout, or foraminous.

25 On the under side of this disk 31 are crossed cleats 34, 35, and it is attached to a substantially U-shape yoke or strap whose upstanding legs 36 have a series of apertures 37 therein and project above the upper edge 30 of the tub when the disk is at the bottom thereof. Preferably the tub is grooved vertically to receive the members 36 so as to bring them flush with the face of the tub and to serve as guides for said members.

35 Hinged to one of the members 36, as by a rule-joint 38, is a link 39, and attached to the latter, as by an overthrow hinged joint 40, is a connecting bar 41 whose opposite end portion has a hasp or the like 42 thereon for 40 engagement with a staple or hook 43 on the opposite member 36.

Mounted on the connecting bar 41, as by 45 hinges 44, is a yoke 45 having a centrally apertured hub portion 46 provided with a collar 47 at its upper end. Swiveled to the hub portion 46, as by a split flanged collar 48, is the hub of a hand-wheel 49. This hand-wheel has a screw threaded bore through which a screw 50 works. Fastened to the 50 lower end of this screw is a cross-block 51 having protuberances 52 on its under side to engage in recesses 53 in the cleats 8 of the tub closure on which said cross-block rests when in operative position.

55 To make clearance for the screw 50 when the squeezer mechanism is in operative position, as shown in Fig. 5, the connecting bar 41 is recessed, as at 54. This is also to permit the yoke 45 to be swung over at right 60 angles to the operative position shown in Fig. 5, so that the connecting bar 41 may be folded down at the side of the tub when not in use, as shown by full lines in Fig. 2 and dotted lines in Fig. 5.

65 In cases where the sides of the tubs taper,

both inside and out, the construction of the squeezer mechanism may be modified, as shown in Fig. 7. In this instance, instead of mounting the follower or squeezer disk 31 on a continuous U-shape strap, a pair of separate members 36^a are employed, and these have hinged thereto, as at 55, short pieces 56 having a slidable connection, such as slot-and-pin, with the under side of the disk. These pieces 56 are connected by hinged 75 links 57 in toggle arrangement so as to break when the disk is raised and thereby permit the lower portions of the members 36^a to leave the grooves in the tub, and to act conversely when the device is lowered in the tub. 80 That is the upper ends of the members 36^a being connected by the cross bar 41, said members 36^a will always remain in engagement with the upper portion of the tub and, consequently, the lower ends of said members 85 36^a must yield inward when the device is raised; and the toggle permits of this. So, when the device is lowered, the toggle striking the bottom of the tub tends to straighten, and, of course, forces the lower portions of 90 the members 36^a into their respective grooves in the tub.

In this modification, also, a flexible or elastic, cupped gasket or ring 58 is placed 95 around the marginal portion of the disk 31 so as to always bear against the face of the tub to retain the articles and yet be sufficiently yieldable as not to retard the upward movement of the device. This ring 58 may be continuous and in one piece, or in separate sections with the ends thereof overlapped or spaced apart, as desired.

From the foregoing description it is noted 100 that an apparatus is produced whereby the washing may be readily accomplished without hindrance of the wringing or squeezer mechanism, as the disk 31 is normally out of the way at the bottom of the tub, and the rest of the mechanism may be folded compactly out of the way at the side of the tub 110 on the side opposite that to which the operator stands.

Then, when the washing has been accomplished, the bridge-plate 15 is swung out of place, and, if desired, onto an adjacent tub 115 as hereinbefore pointed out, it being only necessary to remove the two lid sections 4, 5, and replace them after the agitator is withdrawn from the tub. With the lid back in place, the connecting bar 41, with the parts carried thereby, is moved and set in position as shown in Fig. 5. The cross-block 51 is then brought down on the cleats 8 with the protuberances 52 in the recesses 53, and all is ready for the squeezing operation. By turning the hand wheel 49, the yoke 45 is raised on the screw 50, and, through the cross bar 41 and members 36, the disk 31 is moved upward, thereby squeezing the articles between it and the lid.

It is thus seen that the articles are lifted out of the water in the tub. To remove the articles it only remains to insert a pin 59 in one of the apertures in the member 36 which 5 happens to be exposed directly above the edge of the tub, said pins (there being one for each of the members 36) resting on the tub to support the members in raised position. The pins being thus placed, the hand- 10 wheel is rotated reversely so as to elevate the screw 50 and lift the cross-block 51 off the lid and permit the parts above the lid to be swung out of the way. The lid is then removed and the articles taken from the tub. 15 If it is desired to rinse the articles in the tub, the wash water is drawn off by removing a stopper 60 near the bottom of the tub, and clear water may be poured over the articles on the raised disk 31, or they may be 20 lowered in the tub and the agitator again used, if desired, after which the squeezing operation may be repeated.

In some cases, the pin of the hinge 38 or the hinge 40 may be made removable, so as 25 to detach the connecting bar 41 entirely from the members 36. In this way, the parts of the mechanism carried by said bar 41 may be used interchangeably on a squeezer disk in different tubs, or detached merely to set the 30 said parts aside from the tub instead of folding them thereon as above described.

Obviously, the apparatus admits of considerable modification and changes without in the least departing from the spirit and 35 purpose of the invention as defined by the appended claims. Therefore, it is not limited to the specific construction and arrangement shown in the drawings.

What is claimed is:

40 1. In an apparatus of the character described, a receptacle, a bridge-member hinged on said receptacle, means for supporting said bridge-member in operative position on said receptacle and likewise on an 45 adjacent receptacle, an agitator mechanism on said bridge-member comprising separate agitators disposed axially on opposite sides of said bridge-member to operate in the respective receptacles, and driving means on 50 said bridge-member for said agitator mechanism.

2. In an apparatus of the character described, a receptacle, a bridge-member hinged on said receptacle, means for supporting said bridge-member in operative position on said receptacle and likewise on an adjacent receptacle, a spindle mounted on said bridge-member and extending on opposite sides thereof, an agitator operable on 55 each end portion of said spindle, and driving means on said bridge-member for said spindle.

3. In an apparatus of the character described, a receptacle, a cover therefor, a squeezer disk therein, and a supporting and operating mechanism for said disk, the same comprising vertically movable members working in opposed relation and contiguous to the inner face of the receptacle, a foldable connecting member for the outer ends of 65 said vertically movable members, a supporting member foldable on said connecting member, a hand-wheel swiveled on said supporting member, a screw working through said hand-wheel, and an abutment member 70 on said screw for detachable engagement with said cover of the receptacle, whereby, when said hand-wheel is rotated, said squeezer disk is moved toward said cover. 75

4. In an apparatus of the character described, a receptacle, a cover therefor, a vertically movable squeezer disk therein, foldable operating mechanism for said disk and co-operable with said cover whereby to 80 forcibly lift said disk, and means for holding said disk in raised position independently of said operating mechanism. 85

5. In an apparatus of the character described, a receptacle, a removable cover therefor, a squeezer disk in said receptacle, and a supporting and operating mechanism for said disk, the same comprising vertically movable members working in diametrically opposed grooves in the receptacle, a hingedly mounted cross connecting member at the 90 outer ends of said vertically movable members, a yoke hinged on said cross connecting member so as to stand perpendicularly and at right angles thereto, a hand-wheel swiveled on said yoke, a screw working through 95 said hand-wheel, and an abutment member on said screw for engagement with said cover. 100

6. In a laundry device, a tub, a cover detachably supported at the top thereof, a squeezer disk in said tub, flat strap-like carrier bars for said squeezer disk, said bars being diametrically disposed and lying close to the side wall of the tub, and projecting above the cover, a foldable cross connecting member having a pivotal link engagement with the upper end portions of said bars, a yoke foldable transversely on said cross connecting member, a hand wheel swiveled on said yoke axially of said tub, an operating screw extending axially through said hand wheel with threaded engagement, an abutment member swiveled on said screw and engageable with said cover, and means for securing 110 said carrier bars in raised position. 115

Signed at St. Louis, Missouri, this 16th day of March, 1918.

HARVEY A. EICHELBERGER.
JOHN D. EICHELBERGER.
